UNITED STATES PATENT OFFICE

2,505,517

PIVOTED CAM JAR CAP WRENCH

Waldo H. Banks, Hopedale, Mass.

Application November 9, 1946, Serial No. 708,951

2 Claims. (Cl. 81—3.44)

1

This invention relates to a device adapted to remove the tops of containers such as the so-called screw tops or screw-threaded covers of jars, or the like.

As will presently appear the invention is featured by the provision of novel and unique means whereby the top or cover of a container may be efficiently clamped between jaw-like elements and quickly removed without injury to said top or said container.

Another object is to provide an arrangement susceptible of adjustment to accommodate varying sizes of tops, certain means being supplied to maintain the parts in said adjusted position during the operation of the device.

Still another object is to provide a device of the above nature in which the material is so disposed as to attain a high degree of strength without heavy construction and in which the parts are securely held in assembled relation to present a compact and neat appearance.

Other objects will be in part obvious and in part pointed out hereinafter.

The invention accordingly consists in the features of construction, combinations of elements, and arrangements of parts which will be exemplified in the construction hereinafter described, and the scope of the application of which will be indicated in the subjoined claims.

In the accompanying drawing, in which is shown one of the various possible embodiments of this invention:

Figure 1 is a plan view of the device in position for application to a container top.

Fig. 2 is a side elevation thereof.

Fig. 3 is a view like unto Fig. 1 but illustrating the operative position with the top clamped in the device.

Fig. 4 is an enlarged transverse section taken on the line 4—4 of Fig. 1.

Referring now more in particular to the drawings, wherein similar reference characters denote like parts throughout the several views, the numeral 5 indicates the body portion of the device, conveniently termed a lever, the forward extremity being preferably bent downwardly to form a jaw 6 (see Fig. 2), and presenting a plurality of tooth-like formations 7 to contact the outer depending rim of a lid or closure A. The other end portion of the lever 5 is preferably given a substantially right-angled twist to provide a handle portion 8 its end being fashioned in the manner indicated generally at 9 to open vacuum-sealed covers on jars or caps on bottles, thus increasing the usefulness and efficiency of

2

the tool, as will be readily understood. Said handle portion 8 may be provided with an aperture 8a (see Fig. 2), for supporting the device on a hook, or the like, when not in use.

A slidable member, denoted generally at B, is mounted on said lever 5 its path of operation being between said jaw 6 and the inner end of said handle 8, said slidable member comprising upper plate 10 and lower plate 11 held in spaced relation with the lever 5 therebetween in the manner clearly shown in Fig. 4, studs 12 and 13 being preferably used in the present instance. The assembly of said slidable member B also includes a rotary element 14 eccentrically pivoted to said lower plate 11 by means of said stud 13, said rotary element having a portion of its peripheral face provided with teeth or serrations 15 which cooperate with the teeth 7 of said jaw 6 in a manner to be pointed out hereinafter. Said lower plate 11 is also provided with an opening 16 into which extends a projection or pin 17 borne by said rotary element 14 (see Figs. 1 and 3). At this point it is briefly pointed out that said projection 17 oscillates within the confines of said opening 16 to restrain the movement and clamping pressure of said rotary element 14. As shown in Figs. 2 and 4 said upper plate 10 is provided with a protuberance 18 to facilitate the movement of said slidable member B along said lever 5.

In using the device the parts are in the positions shown in Fig. 1, said slidable member B having been moved along the lever 5 by applying the thumb against said protuberance 18 until the teeth on the peripheral face of said rotary element 14 engage the depending rim of the closure A, the pin 17 being now in the position shown in Fig. 1. This engagement causes said slidable member B to tilt, whereupon said studs 12—13 contact the opposed edges of said lever 5 to bind said slidable member to the lever. A turning movement of the lever counterclockwise causes said rotary element 14 to rotate on its axis 13, the teeth 15 now gripping the depending rim of the closure A to firmly clamp the same between the jaw 6 and the peripheral face of said rotary element 14, this gripping action being insufficient to crush the rim of the closure and the neck of the container since the pin 17 oscillates from the position shown in Fig. 1 to the location indicated in Fig. 3 wherein it will be noted said pin 17 contacts the wall of said opening 16 and prevents further rotation of said element 14. It is also obvious that the aforesaid cooperation between said pin 17 and the wall of the opening 16 prevents the rotary element 14 from over-

riding its highest point of contact with the rim of the closure A and a subsequent loosening of the required gripping action. The respective parts being now in the position indicated in Fig. 3 it is only necessary to continue the counter-clockwise movement of the device to expeditiously effect the removal of tops or closures normally secured to containers in a manner to preclude their removal without resort to undesirable contrivances.

While I have shown a particular embodiment of my invention, it will be understood, of course, that I do not wish to be limited thereto since many modifications may be made, and I, therefore, contemplate by the appended claims to 15 cover any such modifications as fall within the true spirit and scope of my invention.

I claim:

1. A device for removing a container top comprising a lever having a handle portion, a jaw formed at one end of said lever and having tooth formations engageable with a top, a slidable member comprising upper and lower plates mounted on said lever, said lower plate presenting an opening, a rotary element eccentrically 25 pivoted to said lower plate and being movable to clamp the top between said rotary element and

said jaw and a projection borne by said rotary element and engageable with the wall of said opening in said lower plate to restrain the clamping action of said rotary element.

5 2. A device for removing a container top comprising a lever, a jaw disposed at one end of said lever, a member slidably mounted on said lever, said member including a plate presenting an opening, a rotary element eccentrically pivoted to said plate and being movable to clamp the top between said rotary element and said jaw, and means borne by said element and engageable with the wall of said opening in said plate to restrain the clamping action of said rotary element.
